UNITED STATES PATENT OFFICE.

ADOLPH JAGMIN, OF CICERO, ILLINOIS.

DOORCHECK AND THE LIKE.

Application filed July 1, 1921. Serial No. 481,917.

To all whom it may concern:

Be it known that I, ADOLPH JAGMIN, a citizen of the United States, residing at Cicero, in the county of Cook and State of Illinois, have invented certain new and useful Improvements in Doorchecks and the like, of which the following is a specification.

This invention has to do with certain improvements in door checks and the like. It has to do with improvements particularly adapted for use in connection with door checks for controlling the operations of ordinary swinging doors, etc., but the features of the invention may also be used to advantage in connection with checks used for other purposes. Therefore, I do not intend to limit myself to the use of the features of the invention in connection with door checks, except as I may do so in the claims.

Owing, however, to the fact that the features are very well adapted for use in connection with door checks, I have illustrated and will describe said features particularly as used for this purpose.

One of the features of the present invention relates to the provision in door checks of means whereby the check may be locked, so as to prevent the opening of the door by unauthorized persons. More particularly in this connection, a feature is to provide means permitting the adjustment of the door check into such positions that the door may be partially opened, but so as to limit the amount of opening movement to prevent the unauthorized person from actually passing through the door opening. Still more particularly another object is to accomplish the foregoing results in pneumatic or other fluid door checks.

Another object of the invention is to provide in devices of this kind means for limiting the rate of closing movement of the door.

Other objects and uses of the invention will appear from a detailed description of the same, which consists in the features of construction and combinations of parts hereinafter described and claimed.

In the drawings:

Figure 1 shows a longitudinal section through a door check embodying the features of the present invention, showing the plunger in retracted position by means of full lines and in fully closed position by means of dotted lines, parts of the connecting rod being broken away;

Fig. 2 shows a fragmentary section through the adjustment sleeve, being taken on the line 2-2 of Fig. 1, looking in the direction of the arrows and not enlarged scale;

Fig. 3 shows a fragmentary plan view of the inner pivoted end of the door check, being on enlarged scale as compared to Fig. 1;

Fig. 4 shows a plan view of the entire door check in more or less diagrammatic form and on smaller scale as compared to the other figures;

Fig. 5 shows a side elevation of the outer or swinging end portion of the door check, being on enlarged scale as compared to Fig. 1; and

Fig. 6 shows an end view corresponding to Fig. 5.

In the drawings, I have illustrated the door check as applied to a door 7 working in the casing 8. The door check itself includes a tubular cylinder 9 having the inner pivoted head 10 and the outer swinging head 11. The head 10 is pivoted to the door casing at the point 12. For this purpose, use may be made of a bracket 13 secured to the casing and having the outwardly projecting lug 14.

To the upper portion of the door itself is connected a reach rod 15. This reach rod has its outer end curved up and around as at 16 and pivotally connected to the door check at the point 17 in the manner to be presently explained. In order to adjust the parts, the reach rod 15 may have its body portion 18 located within the tubular bracket 19 secured to the door by means of the plate 20; and a set screw 21 serves as a means for locking the reach rod to the tubular bracket 19 at any desired position of adjustment.

Within the cylinder 9 there operates the plunger 22. This plunger is connected to the piston rod 23 which works through the swinging head 11. The reach rod connects to the piston rod at the pivotal point 17 previously referred to.

A spring 24 is interposed between the plunger 22 and the abutment 25. This abutment is carried by a sleeve 26 which is threaded through the swinging head 11 and may be moved in and out in order to adjust the position of the abutment 25. In this way the compression of the spring 24 may be adjusted.

The sleeve 26 has an enlarged head 27 which is socketed to receive a packing gland 28. This packing gland is normally forced down by means of the cap screw 29 in the 5 well known manner.

The pivoted head 10 is provided with an air chamber 30 communicating with the outside atmosphere by means of an opening 31, and a port 32 provides communication between the chamber 30 and the interior of the cylinder 9. A valve 33 normally seats against the inner face of the port 32 to close the same. This valve is provided with the pin 34 reaching into the air chamber 30 and having an enlarged head 35 against which seats a spring 36. The inner end of said spring bears against a cross bar 37, so as to provide the necessary pressure for normally holding the valve 33 in the closed position. 20 When the plunger 22 is drawn inwards against the force of the spring 24 during the opening of the door, the air flows into the cylinder through the port 32 and past the valve 33. Said valve then seats and the 25 plunger 22 can not move backwards except by compressing the air, unless said air is allowed to flow out from the cylinder.

I have provided another air valve 38 in communication with the inner end of the 30 cylinder by means of a port 39. Said valve 38 may be rocked by means of a lever 40 and against the force of a spring 41. When the lever stands in the normal position, as indicated by said spring, the valve is fully 35 closed and the plunger is thus prevented from moving back within the cylinder more than a limited distance.

A valve 42 works within the port 31. This valve is connected to a rock arm 43 pivoted to 40 a bracket 44 at the point 45. A spring 46 normally tends to rock the arm 43 so as to force the valve 42 downwards and thus completely close the opening 31. This will effectively prevent the entrance of air into the 45 cylinder and will thus interpose a heavy resistance against the movement of the plunger 22.

As the plunger 22 is drawn inwards by the opening of the door, the air behind it 50 must either leave the cylinder or be compressed. The air leaving or entering the back side of the cylinder is controlled by means of a valve 47 connected to the back side of the cylinder by means of a port 48. 55 The valve 47 may be rocked by means of a lever arm 49, a spring 50 normally tending to draw said lever arm over in the manner shown in Fig. 6, so as to fully close the valve. When the valve is so closed the air is drawn 60 in the back side of the cylinder and heavy resistance is thus interposed to the movement of the plunger.

I have provided means for controlling all 65 of the valves 38, 42 and 47 from a distant point and in a very convenient manner by

means of a person located on that side of the door which is to be protected against intrusion. This means, in the arrangement illustrated, includes an operating lever 51 pivoted to the door casing at the point 52. 70 Said lever may be set into any one of a number of different positions by means of a pin passed through a hole 53 in the lever and through any selected one of a number of holes 54 in a stationary segment. The lever 75 is connected to the various valves by means of the cords 61, 62 and 63 which connect to the valves 38, 42 and 47 respectively. These cords pass over suitable pulleys whose positions and mountings will naturally be dictated largely according to the particular requirements of the installation. 80

As long as the operating lever 51 stands in the position illustrated in Fig. 1, all of the valves are in the closed position, so that the check is effectively locked against opening the door more than a very slight distance. This is the normal condition. In order to lock the valves 38 and 47 normally in this position, I have provided the pins 55 and 56 90 which are normally spring pressed by the springs 57 and 58 into such positions as to interfere with the opening movements of their respective valves. The cords 59 and 60 connect said pins to the operating lever 51, so 95 that they will be withdrawn at the same time that an effort is made to open the valves and in order to permit the valves to be opened.

While I have herein shown and described 100 only a single embodiment of the features of my present invention, still I do not limit myself to the said embodiment except as I may do so in the claims.

I claim:

1. In a device of the class described, the combination of a cylinder, a pivotal mounting for one end thereof, a plunger working within said cylinder, a piston rod connected to said plunger and working through the other end of the cylinder, a stuffing box for the piston rod, an adjustable sleeve surrounding the piston rod and extending through said end of the cylinder to the interior thereof, a spring interposed between the inner end of said sleeve and plunger, whereby the pressure on said spring may be adjusted by adjustment of the sleeve, an air chamber in communication with the pivoted end of the cylinder, there being a port establishing communication between said air chamber and the outside atmosphere, a valve controlling said port, a valve interposed between the air chamber and the inner end of the cylinder and serving to permit the free movement of air from the air chamber into the cylinder while preventing backward movement of said air from the cylinder, another valve controlling direct communication from the pivoted end of the cylinder 110 115 120 125 130

and to the outside atmosphere, another valve controlling direct communication from the swinging end of the cylinder to the outside atmosphere, means for normally retaining 5 all of the valves in closed position, and means under the control of the operator permitting the valves to be opened a predetermined amount, substantially as described.

2. In a device of the class described, the 10 combination of a cylinder, a pivotal mounting for one end thereof, a plunger working within said cylinder, a piston rod connected to said plunger, and working through the other end of the cylinder, a spring interposed between the plunger and the head of the cylinder, an air chamber in communication with the pivoted end of the cylinder, there being a port establishing communication 15 between said air chamber and the outside atmosphere, a valve controlling said port, a valve interposed between the air chamber and the inner end of the cylinder and serving to permit the free movement of air from the air chamber into the cylinder 20 while preventing backward movement of said air from the cylinder, another valve controlling direct communication from the pivoted end of the cylinder to the outside atmosphere, another valve controlling direct 25 communication from the swinging end of the cylinder to the outside atmosphere, means normally retaining all of the valves in closed position, and means under the control of the operator permitting the valves 30 to be opened a predetermined amount, substantially as described.

3. In a device of the class described, the 35 combination of a cylinder, a pivotal mounting for one end thereof, a plunger working within said cylinder, a piston rod connected to said plunger and working through the other end of the cylinder, a spring interposed between the plunger and the head of the cylinder, an air chamber in communication 40 with the pivoted end of the cylinder, there being a port establishing communication between said air chamber and the outside atmosphere, a valve controlling said port, a valve interposed between the air chamber and the inner end of the cylinder and serving to permit the free movement of 45

air from the air chamber into the cylinder while preventing backward movement of said air from the cylinder, another valve controlling direct communication from the pivoted end of the cylinder to the outside atmosphere, another valve controlling direct communication from the swinging end of the cylinder to the outside atmosphere, and means under the control of the operator permitting the valves to be 50 opened a predetermined amount, substantially as described. 55

4. In a device of the class described, the combination of a cylinder, a pivotal mounting for one end thereof, a plunger working within said cylinder, a piston rod connected to said plunger and working through the other end of the cylinder, an air chamber in communication with the pivoted end of the cylinder, there being a port establishing communication between said air chamber and the outside atmosphere, a valve controlling said port, a valve interposed between the air chamber and the inner end of the cylinder and serving to permit the free movement of air from the air chamber into the cylinder while preventing a backward movement of said air from the cylinder, another valve controlling direct communication from the pivoted end of the cylinder to the outside atmosphere, another valve controlling direct communication from the swinging end of the cylinder to the outside atmosphere, and means under the control of the operator permitting the valves to be 60 opened a predetermined amount, substantially as described. 65

5. In a device of the class described, the combination of a cylinder, a pivotal mounting for one end thereof, a plunger working within said cylinder, a piston rod connected to said plunger and working the other end of the cylinder, a valve controlling direct communication from the pivoted end of the cylinder to the outside atmosphere, another valve controlling direct communication from the swinging end of the cylinder to the outside atmosphere, and means under the control of the operator permitting the valves to be 65 opened a predetermined amount, substantially as described. 70

ADOLPH JAGMIN.
